UNITED STATES PATENT OFFICE.

HARRY C. CLAY, OF COLUMBUS, INDIANA, ASSIGNOR TO THE REEVES & COMPANY, OF SAME PLACE.

STRAW-BURNING FURNACE.

SPECIFICATION forming part of Letters Patent No. 660,181, dated October 23, 1900.

Application filed March 19, 1900. Serial No. 9,190. (No model.)

To all whom it may concern:

Be it known that I, HARRY C. CLAY, a citizen of the United States, residing at Columbus, in the county of Bartholomew and State 5 of Indiana, have invented a new and useful Straw-Burning Furnace, of which the following is a specification.

My invention relates to an improved form of arch for straw-burning furnaces.

10 The object of my invention is to produce a fire-arch for straw-burning furnaces of such character that it may be readily removed from or inserted in the fire-box and of such form that expansion and contraction may take 15 place without opening the joints.

The accompanying drawings illustrate my invention.

Figure 1 is a transverse section on line 1 1 of Fig. 2. Fig. 2 is a longitudinal section on 20 line 2 2 of Fig. 1. Fig. 3 is a detail section, on an enlarged scale, on line 3 3 of Fig. 2.

In the drawings, 4 indicates the fire-box, which may be of any desired form and from which lead the usual tubes 5. In the con- 25

struction ordinarily used the grate 6 is over-hung by a fire-arch which consists of one or more sections of tile, each of which extends entirely across the fire-box. In such a con- 30

struction the tiles must be supported loosely 35 at the side, so as to allow for expansion and contraction of the several parts, and when so supported it is found exceedingly difficult to introduce new tiles in place of broken ones or to remove the tiles, so as to adapt the fur- 40

nace for burning fuel other than straw. In my construction, therefore, I secure to the side wall 7 of the fire-box a series of pins 8, which project a short distance into the fire-box. Upon these pins I hang a pair of angle-irons 45

9, having a flange 10 projecting horizontally inward, the said angle-irons being mounted upon walls 7 at any desired angle to the grate-bars. I then provide a pair of tiles 11 and 12, each of which has upon its outer edge a lon- 50

gitudinal groove 13, adapted to receive flange 10 of the adjacent angle-bar. The inner edge 14 of the tile 11 is convex in cross-section, while the inner edge 15 of the tile 12 is con- 55

cave in cross-section, so as to receive the edge 50

14 and form therewith a knuckle-joint. The

combined length of the two tiles 11 and 12 is somewhat greater than the width of the fire-box, so that when placed in position there will be a continuous, although slight, pressure outward, thus holding the angle-bars 9 in position. Any expansion or contraction of the tiles or change of dimension of the fire-box will be compensated by the automatic action of the knuckle-joint between the two tiles, and a tight joint will also be maintained between the inner ends of said tiles and also between the outer edges of said tiles and their supporting angle-bars. The flange 10 of the angle-bar being entirely inclosed in the groove 13 is entirely protected from the action of heat from the furnace. The tiles 11 and 12, being but little greater than one-half the width of the fire-box, may be readily removed from the furnace, and in view of the fact that no bolts are used to support the angle-bars in position said tiles may be easily removed and the supporting angle-bars may be also easily removed, so as to quickly fit the furnace for use in burning fuel other than straw.

It will be readily understood that the tiles 75 may be made in as many longitudinal sections as desired.

I claim as my invention—

1. In a furnace having fire-arch supports projecting therein, a fire-arch consisting of a 80 pair of tiles having mating adjacent edges arranged to allow a relative angular movement without breaking the joint, and so formed upon their outer edges as to receive and protect the projecting supports. 85

2. In a furnace having fire-arch supports projecting therein, a fire-arch consisting of a pair of tiles the inner edge of one of which is convex in cross-section, and the inner edge of the other of which is correspondingly con- 90

cave in cross-section, and means carried by the outer edges of each of said tiles for receiving and protecting the projecting supports. 95

3. In a furnace, the combination with the fire-box, of an angle-iron detachably hung upon each side of its fire-box, and a fire-arch consisting of two tiles hinged together at their adjacent edges and adapted to rest at their outer edges upon said angle-irons, the ar- 100

angement being such that said angle-irons are held in position by the normal tendency of elongation of the arch.

4. In a furnace, the combination with the fire-box, of one or more pins extending into said box from opposite sides thereof, an angle-iron hung upon each side of pins, and a fire-arch consisting of two tiles hinged together at their adjacent edges and adapted to rest at their outer edges upon said angle-irons, the arrangement being such that said angle-irons are held in position on their pins by the normal tendency of elongation of the arch.

5. In a furnace, the combination with the fire-box, of a flange projecting into the fire-box from each side thereof, and a fire-arch consisting of two tiles hinged together at their adjacent edges and each provided on its outer edge with a groove adapted to receive the adjacent flange, the arrangement being such that said flanges are protected from the heat of the furnace.

HARRY C. CLAY.
